(57) **CLAIM**

The ornamental design for a knitting needle, as shown and
described.

DESCRIPTION

FIG. 1 is a front view of the new design for a knitting needle,
FIG. 2 is a left side view of FIG. 1,
FIG. 3 is a back view of FIG. 1,
FIG. 4 is a right side view of FIG. 1,
FIG. 5 is a top view of FIG. 1,
FIG. 6 is a bottom view of FIG. 1,
FIG. 7 is a front right perspective view of FIG. 1; and,
FIG. 8 is a back left perspective view of FIG. 1.
The larger oval and the arrays of small ovals represents a
graphic on an otherwise planar surface of the knitting
needle.

1 Claim, 2 Drawing Sheets
